UNITED STATES PATENT OFFICE

MALCOLM HARD, OF FLUSHING, NEW YORK, ASSIGNOR TO THE SUPERHEATER COMPANY, OF NEW YORK, N. Y.

METHOD OF MANUFACTURING SUPERHEATER HEADERS

Application filed July 12, 1928. Serial No. 292,263.

This invention relates to locomotive superheater headers and has for its purpose the provision of an improved structure of this kind.

As is well understood by those familiar with this art, the header for the locomotive superheater is now universally located in the upper portion of the smoke-box and the tubular superheater elements or units which are attached to its underside extend in to the flues or fire tubes. The ordinary practice hitherto has been to make these headers of a high grade cast iron and this has proved eminently satisfactory and failures of such headers are almost unheard of. It is true, however, that if steel, particularly plate steel, could be employed in the manufacture of the headers, considerable weight might be saved. Attempts to make these headers of cast steel have not proved very satisfactory on account of the difficulty of keeping the castings free from blow holes. If it were not for this difficulty, cast steel headers would be quite ideal. The art of autogenous welding has progressed far enough to make it entirely feasible and safe to weld up steel plates into such headers. It is of course desirable to keep the form of the header closely similar to the form of the cast header hitherto used so that the tubular elements may be freely interchangeable. If this precaution is not taken, railroads would be obliged to carry on hand stocks of spare units or elements to suit both forms. When an attempt is made to produce a steel plate header following existing standards closely enough for the purpose just spoken of, it will be found that the matter is not free from difficulty. The present invention furnishes a header of plate steel of such configuration that the tubular units designed for use with the present form of cast "T-bolt" headers may be applied directly to it.

The invention is illustrated in the drawings herewith, in which Fig. 1 is a front elevation of a header according to the present invention, a portion of it being in section on the line 1—1 of Fig. 2 and two ends of superheater elements being shown connected to the header; Fig. 2 is a top view

of the header, the left half being a section on line 2—2 of Fig. 1; Fig. 3 is a fragmentary view illustrating a portion of one of the sheets used; Fig. 4 is a section on line 4—4 of Fig. 1; and Fig. 5 is a fragmentary sectional view on line 5—5 of Fig. 1.

In building a header according to my invention, I form first a number of members 1—1 which are to serve as partitions, these members being most conveniently made out of lengths of rolled T steel. The outer ends of arms of the T are for this purpose turned in a direction away from the vertical stem, as will be clear from an inspection of Fig. 1. The resulting structure may be considered as an inverted Y. The upper edge of these T lengths is cut to slope down in each direction from the middle along the lines 2—2 (see Fig. 4).

To the partitions just described are welded the base or bottom plates 3—3 in the position clearly indicated in the drawings. Between adjacent plates 3—3 are left the slots 4—4 which are somewhat narrower than the distance between the downwardly turned portions of the T's. Through these plates 3 have been drilled the holes 5—5 through which the tubular elements 6 are to communicate with the interior of the header. The general arrangement of these holes 6—6 is the standard one.

A partition 7 is next formed of a length equal to the length of the header. This partition has a vertical portion 7 and two series of members 7a and 7b extending alternately in opposite directions from the lower end of the vertical portion. This plate is produced most conveniently by taking a plate of the required dimensions and sawing slits in from one of its long edges to the required distance and then bending the resulting flaps in opposite directions. The exact angle to which the flaps are bent with respect to the vertical portion 7 is such that the completed member may be set on the partitions 1, the edges of each flap contacting with adjacent ends of the partitions 1 and the length of the flaps being such that their ends coincide with the ends of the partitions 1. The mem-

ber 7 is set into position just described and the edges mentioned are welded together.

After the partitions 1-1 have been welded to the bottom plates 3, the front 8 and the back 9 are welded into place. Each of these members has the form of a flat plate with portions 10-10 cut out to receive the ends of the partitions 1-1. The partitions 1 do not extend entirely through the openings 10 but extend only part way into them, as shown in Fig. 5. This makes the welding of the plates 8 and 9 to the partitions quite easy in the manner indicated in Fig. 5.

The next step is to weld on the end pieces 13 and 14. Their lower edges are welded to the outer bottom pieces, and the ends of the partition 7 are welded to them.

The final step is to weld in the top. This is made up of two portions 12a and 12b. One of these is welded to the upper edge of partition 7, to the ends 13 and 14, and to the upper edge of front plate 8, and the other is welded to the upper edge of the partition 7, to the ends 13 and 14, and to the upper edge of rear plate 9.

Connections for admitting and taking away the steam are next to be provided. This is done by cutting holes into the appropriate sheets and welding in the connecting pieces. 15 is the connection for the dry steam pipe. This is a cast steel structure and is welded in along the line 16, the plates of the header having been cut through along this line by means of an oxyacetylene torch or other means for this purpose.

17-17 are the two connections for the steam pipes which are welded in along the lines 18-18, the plates of the header having been cut away along these lines for this purpose.

The cutting away of the header plates along the lines 16 and 18 may be performed either before the header is assembled or afterwards, the preferred method being the latter.

In Fig. 1 is illustrated one pair of tube ends 6-6, their enlarged heads 19-19 bearing against the outer ends of a pair of openings 5-5. The bolt 20 has its head in the space between the branches of the T, the shank of the bolt extending through the slot 4 and the nut at the lower end of the bolt bearing against the yoke or clamp 21. This yoke presses upwardly as the nut is pulled up against the two washers 22-22 and thus indirectly against the enlarged heads 19-19. This is all in accordance with common practice and is spoken of in detail merely to bring out clearly the fact that the new header is adapted to be used in exactly the same way as the cast iron header which has been standard so far.

It will be obvious that some changes can be made in the header itself or in the manner

of making it without departing from the spirit of the invention.

I claim:

1. The process of making a steel-plate header comprising the steps of welding vertical transverse partitions to a rectangular bottom; forming a longitudinal steel-plate partition with a continuous vertical portion and smaller rectangular portions extending alternately in opposite directions from the lower edge of the first portion, the dimensions and conformation of these parts being such that the second-named partition may be set on the first named partitions with the top edges of the latter abutting against the lateral edges of the oppositely extending portions of the former; welding said edges together; welding a front and a back to the bottom and to the outer edges of the first-named partitions and of the oppositely extending portions; welding a top to the upper edges of the front and back and of the longitudinal partition; and, welding in steel plates to close the ends.

2. The process according to claim 1, the vertical transverse partitions being given the shape of inverted Y's and the bottom being made in sections spaced apart to form slots, each slot lying between the branches of a Y and being narrower than the distance between the branches.

3. The process of manufacturing a structure of the class described, comprising taking a generally rectangular piece of sheet-metal, making a series of parallel spaced cuts from one edge inward, bending the resulting flaps alternately in opposite directions, and assembling other pieces with the first named one to form two longitudinal chambers on opposite sides of the uncut portion of the first named piece and a third chamber under the other two.

4. The process according to claim 3, comprising the further steps of welding vertical partitions into said third chamber dividing it into a series of spaces communicating alternately with the two upper chambers.

MALCOLM HARD.
